Lillian Farber, Toronto, Ontario, Canada, assignor, by mesne assignments, to Noell Products Company, New York, N. Y., a limited partnership

Application November 19, 1945, Serial No. 123,905
In Canada June 12, 1945

Term of patent 3½ years

(Cl. D86—10)

To all whom it may concern:

Be it known that I, Lillian Farber, a British subject, residing at the city of Toronto, in the county of York, Province of Ontario, Dominion of Canada, have invented a new, original, and ornamental Design for a Hand Mirror, of which the following is a specification, reference being had to the accompanying drawing, forming part thereof.

The back of the mirror, not shown, is substantially plain.

I claim:

The ornamental design for a hand mirror, as shown and described.

LILLIAN FARBER.
